UNITED STATES PATENT OFFICE.

CHARLES F. LARSEN, OF NEW YORK, N. Y.

DESIGN FOR AN IGNITER FOR SMOKERS' USE.

Application filed February 23, 1927. Serial No. 20,851. Term of patent 7 years.

To all whom it may concern:

Be it known that I, CHARLES F. LARSEN, a citizen of the United States, residing at New York, in the county and State of New York, have invented a new, original, and ornamental Design for an Igniter for Smokers' Use, of which the following is a specification, reference being had to the accompanying drawing, forming part thereof.

Fig. 1 is a plan view of an igniter for smokers' use embodying my new design;

Fig. 2 is an elevational view of the same; Fig. 3 is a side view of the same; and Fig. 4 is a bottom view of the same.

I claim:

The ornamental design for an igniter for smokers' use, as shown.

In testimony whereof I have hereunto set my hand.

CHARLES F. LARSEN.
